UNITED STATES PATENT OFFICE.

OTTO LINDSTROM AND TOIVO MAKELA, OF INDIANAPOLIS, INDIANA, ASSIGNEES OF
ONE-THIRD TO JOHN HAMLIN, OF MUNCIE, INDIANA.

DRAWING-IN POWER-HAMMER DIE.

1,290,258.

Specification of Letters Patent.

Patented Jan. 7, 1919.

Application filed December 29, 1917. Serial No. 209,421.

To all whom it may concern:

Be it known that we, OTTO LINDSTROM and TOIVO MAKELA, citizens of Finland, residing at Indianapolis, in the county of Marion and State of Indiana, have invented a new and useful Improvement in Drawing-In-Power-Hammer Dies, of which the following is a specification, reference being had to the accompanying drawings and to the letters and figures of reference marked thereon.

This invention relates to dies that are designed to be used in a power hammer for shaping or re-shaping sheet metal, the invention having reference more particularly to dies whereby portions of a sheet or plate of metal may be drawn in or contracted, either to effect a reduction in width of the sheet or plate if finished so as to be flat, or to cause curvature of the sheet or plate when desired.

An object of the invention is to provide means whereby drawing-in operations on sheet or plate metal may be expeditiously and efficiently performed without necessitating the use of costly form dies in a press, more particularly when curved forms are required.

Another object is to provide improved means whereby sheet metal may be formed into curved shapes, whether regular or irregular curvature, and more rapidly and efficiently than by the well known hand-hammering process.

A further object is to provide simple and inexpensive dies which shall be adapted to be used for producing various curved shapes of sheet metal by the hammering process and which shall be durable and economical in use.

With the above-mentioned and other objects in view, the invention consists in a pair of novel hammer dies whereby portions of sheet metal may be drawn in or structurally contracted and whereby also plates may be formed into dish shape or into bowl shape or into various curved shapes that may be desired. And the invention consists also further of the parts and combinations and arrangements of parts as hereinafter particularly described and further defined in the accompanying claims.

Referring to the drawings, Figure 1 is a fragmentary front elevation of a well-known type of power-hammer which for the pur-

pose of illustrating the invention is provided with the improved dies; Fig. 2 is a side elevation of Fig. 1; Fig. 3 is an elevation of one of the improved dies, that portion commonly used as the front portion being shown; Fig. 4 is a side elevation of the die shown in the preceding figure which preferably is the lower one of the pair of dies; Fig. 5 is a plan of the face of the upper one of the pair of dies; Fig. 6 is a central vertical section of the pair of dies on the line VI-VI on Fig. 2; Fig. 7 is a plan of the face of the lower one of the dies; Fig. 8 is a section of the upper one of the dies on the line VIII-VIII on Fig. 5; Fig. 9 is a side elevation of the improved dies in operation in the power-hammer machine which is shown by broken lines; Fig. 10 is a front view of the dies as in operation in a hammer machine which is indicated by broken lines; Fig. 11 is a rear elevation of the improved dies as when working on a sheet of metal; Fig. 12 is a central section of the dies as when working on a sheet of metal; Fig. 13 is a top plan of a plate which is partially curved and indicated as being upon the bottom die; and, Fig. 14 is a rear elevation of a pair of dies, the upper one being partially broken away, slightly modified to illustrate duplication of essential features thereof.

Similar reference characters on the different figures of the drawings indicate like parts or elements hereinafter referred to in detail.

A power hammer with which the improved dies are advantageously used for working on metallic sheets of such thickness as is capable of being shaped by the power and capacity of such hammering machine comprises a suitable upright column or support 1 which supports an arm 2 having an anvil 3 thereon, the latter being adapted to hold a bottom or lower die. Above the arm a frame 4 is supported also by the column or support 1 and it has a guide head 5 thereon and rotatably supports a suitably driven shaft 6 which has a head 7 thereon provided with a crank pin 8 to which a pitman or connecting rod 9 is connected, the latter being secured to a bow spring 10. A hammer body 11 is vertically guided by the head 5 and connected with the bow spring by means of suitable links 12 and 13, the hammer body being adapted to

hold a top or upper die opposite to the bottom or lower die.

Two improved dies 14 and 15 are provided for the purpose intended, the die 14 preferably being used as the bottom or lower die and is secured with its face uppermost to the anvil 3, the companion die 15 being secured with its face undermost to the hammer body 11. The lower die 14 has an approximately flat central face 16 upon the rear portion of which is a projecting rib or ridge 17 that has a sloping top 18 which gradually merges into the flat face 16. The rib is relatively broader at its base than at its top and it conveniently extends to the rear side of the die. The top of the die has a rounded edged portion 19 so that concave surfaces may be worked thereon. The face of the top die 15 has an approximately flat central portion 20 in which is a groove or recess 21 having a sloping bottom 22 that extends gradually from the face 20 and progressively deeper into the body of the die to the rear side thereof to receive the rib or ridge 17 without contact therewith, the groove or recess being sufficiently capacious to permit the rib to force a portion of sheet metal therein without forcing the metal to the bottom of the groove when the metal is forced to the face 16 and the face 20 is forced hard on to the metallic sheet. The face of the upper die has a rounded edge portion 23 so as to clear the metallic sheet when being handled between the dies.

35 The dies may have more than one rib or groove, as will appear in Fig. 14 in which a pair of dies 14' and 15' appear, the lower die having two additional ribs or ridges 24 and 25, the companion die having additional grooves or recesses 26 and 27 to receive the additional ribs.

As an illustration of the manner of using the improved dies, a sheet or plate of metal is placed upon the bottom die 14 with the portion 28 of the sheet that may be flat and so remain foremost or toward the operator who moves the sheet forward and rearward repeatedly, each forward movement being intermittent with each hammer stroke, so as to bring the rearward end thereof over the rib or ridge 17, the hammer being stopped while moving the sheet rearward; and, if the flat portion of the sheet be forcibly drawn downward by hand the rearward portion of the sheet may be formed with a curvature 29 on which a rib or crease 30 required in the drawing-in process is formed. As the sheet or plate is progressively drawn forward it is first creased by the rib 17 forcing the metal of the sheet into the groove 21, the metal of the sides of the crease being upset in the shallow portion of the groove, and the crease being immediately drawn onto the flat face 16 of the die on which the crease 65 is hammered flat, thus drawing in or con-

tracting the metal by condensing the molecular structure thereof so as to reduce the width of a portion of the sheet or plate. The sheet is repeatedly shifted laterally until drawn in as may be desired and may be left in flat condition throughout if kept in horizontal position on the die. In Fig. 11 the rear edge of the metal sheet is seen as being drawn in and curved, 31 indicating the forward portion of the sheet, and 32 the curved rearward edge portion on which a corrugation 33 is formed by the dies to be immediately drawn forward, the metal of the sides of the corrugation condensed and the metal flattened on the flat face at the lower end of the rib 17. In Fig. 12, 34 indicates the forward portion in position to be hammered on the flat face of the die, 35 indicating the rearward portion of the sheet which is curved and formed with a corrugation 36 to be progressively condensed at its sides in the groove and brought to the flat face 16 and hammered flat thereon. In Fig. 13, 37 indicates the flat unchanged portion of the metallic sheet or plate and 38 a curved portion resulting from having been operated upon by the dies. In some cases the sheet or plate of suitable pattern is given a dished shape 39 as appears in Fig. 10 by continuous shifting of the metal sheet in a rotary direction and forward and backward upon the bottom die, repeating the operation oftener near the edge portion of the sheet or dish, and in such case the middle portion of the completed dish or bowl may be left flat or may be curved as well as the side portions thereof. In producing the hemispherical dish the sheet is tilted on the lower die. The dies are particularly useful for shaping sheet metal, automobile bodies when they are required to have curved portions, or for drawing in and eliminating accidental indentations in the metal, and especially when it is desired that each body have a distinctly original or special curved design different from all other bodies.

It will be apparent that after a corrugation or crease is formed the metal of the sides thereof stands up at an inclination, yet sufficiently approximating "on edge" arrangement to permit the hammer blows to condense the molecular structure of the metal in one direction and thus reduce the height of the side, and therefore when the crease is flattened the width of the sheet is less than before the treatment; or, if the sheet is not flattened the metal comprising the rim or side portion of the disk or bowl is drawn in as it is bent up; it being understood that the hammer does not exert sufficient force to stretch or expand the metal in the direction of its width or length in the process of flattening when this is done, only a few blows being necessary to flatten the sheet.

Having thus described the invention, what is claimed as new is—

1. Means for drawing-in operations on sheet metal including a pair of coöperating dies having correlated facial contours adapted for creasing the metal, condensing the metal of the sides of the creases, and subsequently flattening the creases, and means for controlling the dies.
  - 10 2. Means for drawing-in portions of sheet metal including a pair of coöperating dies operating one upon another, one of the dies having a ridge and the other a relatively larger groove to loosely receive the ridge for creasing and condensing the metal, the dies having flat faces for hammering down the creases, and means for controlling the dies.
  - 15 3. Drawing-in power hammer dies including a pair of dies having each an approximately flat face, the face of one of the dies having an inclined ridge thereon, the face of the remaining one of the dies having a groove therein that has an inclined bottom and is deeper than the height of the ridge to freely receive the ridge and a layer of metal thereon.
  - 20 4. Means for drawing-in portions of sheet metal including a stationary die and a movable die, each die having an approximately flat face, one of the dies having a ridge extending upward at an inclination from the middle portion of the flat face, the remaining
  - 25
  - 30
- one of the dies having a groove extending from the middle portion of the flat face at an inclination thereto and adapted to loosely receive the ridge and a portion of the sheet metal thereon, to crease and condense the metal, the flat faces being adapted to flatten the creases.
5. The combination with a power hammer machine having an anvil and also a movable hammer body, of a pair of drawing-in dies secured respectively to the anvil and the hammer body, each of the dies having an approximately flat central face portion, the edge portions of the faces being receding and curved, one of the dies having a ridge on one side of the central face portion, the top of the ridge extending at an inclination from the middle of the flat face portion, the remaining one of the dies having a groove on one side of the central face portion, the bottom of the groove extending at an inclination from the middle of the flat face portion of the die, the groove being relatively larger than the ridge to loosely receive the ridge.
